United States Patent Office

Des. 175,000
Patented June 21, 1955

175,000

DESK STAND

Dorothy Stone, Brookline, Mass.

Application October 27, 1954, Serial No. 32,838

Term of patent 7 years

(Cl. D74—1)

Fig. 1

To all whom it may concern:

Be it known that I, Dorothy Stone, a citizen of the United States, residing at Brookline, in the county of Norfolk and State of Massachusetts, have invented a new, original, and ornamental Design for a Desk Stand, of which the following is a specification, reference being had to the accompanying drawing, forming part thereof.

I claim:

The ornamental design for a desk stand, as shown.
